United States Patent

Des. 241,883
Patented Oct. 12, 1976

241,883

INFUSION PUMP

Phillip W. King, Cheshire, Conn., assignor to American
Home Products Corporation, New York, N.Y.

Filed Mar. 12, 1975, Ser. No. 557,547

Term of patent 14 years

Int. Cl. D24—02

U.S. Cl. D83—1 F

FIG. 1

F I G . 2

FIG. 1 is a front perspective view of an infusion pump embodying my new design;

FIG. 2 is a rear perspective view thereof;

FIG. 3 is a rear perspective view taken at an alternate position;

FIG. 4 is a bottom plan view thereof; and

FIG. 5 is an elevational view of one end thereof.

I claim:

The ornamental design for an infusion pump, as shown.
